UNITED STATES PATENT OFFICE.

FRANK MARION, OF LEBANON, NEW HAMPSHIRE, ASSIGNOR OF ONE-HALF TO JAMIE E. JACOBS, OF BARRE, VERMONT.

ROTARY PUMP.

Application filed December 8, 1923. Serial No. 605,636.

To all whom it may concern:

Be it known that I, FRANK MARION, a citizen of the United States, residing at Lebanon, in the county of Grafton and State of New Hampshire, have invented certain new and useful Improvements in Rotary Pumps, of which the following is a specification.

The object of this invention is to effect improvements in pumps of that type in which a cylindrical rotor with radially extended spring-pressed vanes is mounted to rotate concentrically in a cylindrical casing, and at one side an abutment is provided through which water is drawn and discharged, and which also serves as a cam to bear the vanes inwardly, and to maintain contact with the rotor between the vanes and thus separate the intake from the discharge side of the pump. It is a specific object of the invention to effect improvements in the abutment device, to the end that a dependable abutment will be provided which will be liable in a minimum degree to impairment by wear, and will function efficiently to compensate for wear on the face exposed to the rotor and vanes. It is an important purpose to provide an abutment of this character which will coact with the vanes to obviate the liability of uneven wear of the vanes tending to produce irregularities in the surface, and cause the vanes to wear evenly, so that at all times they will fit snugly against the cylindrical walls of the casing. It is a further important object to provide a novel construction of vane and abutment in combination, whereby the vanes, having passages therein for relief of pressure behind the vanes when retracted, and opening through the outer ends of the vanes, will coact in a peculiar way with the openings in the abutment to obviate liability of uneven wear in surfaces of the abutment and casing and also prevent shearing wear, or liability of the parts to interlock.

Additional objects, advantages and features of invention reside in the particular construction, arrangement and the combination of parts as will hereinafter be understood from the description and drawings, in the latter of which,

Figure 1 is a vertical sectional view in the major plane of a pump constructed in accordance with my invention,

Fig. 2 is a perspective view of the abutment element,

Fig. 3 is a fragmentary cross section on the line 2—2 of Fig. 1,

Figure 4 is a projected plan of the perimetral plane of the pump chamber, the vane being dotted thereover.

Figure 5 is an end face view of one of the vanes.

There is illustrated a pump comprising a body 10 which may be open at both sides and closed at these sides by plain casing heads in accordance with familiar practice in such constructions, these heads not being illustrated. The casing is formed with a cylindrical chamber 11, and a footing 12 by which it may be secured upon a foundation. From the chamber 11, at the upper part, there is an extension vertically, forming a rectangular abutment chamber 13, having parallel sides intersecting the perimetral inner surfaces of the chamber 11, and extending a suitable distance outward from this intersection. Through the parallel walls mentioned, tapped openings are formed in coaxial alinement, providing inlet and outlet connections 14 and 15, respectively. In the top of the chamber 13, an extension 16 having parallel sides transversely of the casing is formed, which receives a central boss or rib 17 of an abutment 18 which fits snugly in the chamber 13, but slidably for movement radially with respect to the chamber 11. A cylindrical rotor 19 is concentrically mounted for rotation in the chamber 11, being of a diameter less than that of the chamber, thus providing a passage 20 between the casing and rotor of an even dimension throughout the major part of its length, this space being restricted only by the abutment 18, which is formed with an arcuate inner face 21 adapted to bear upon the rotor centrally of the abutment with its end portions adjacent the parallel walls of the chamber 13 first mentioned, nearly or quite alining with the perimetral wall of the chamber 11. In the ends of the abutment 18 cored inlet and outlet passages 22 and 23 respectively, are formed, opening into communication with the openings 14 and 15 respectively. Between these passages 22 and 23 and the chamber 11, a grill is formed, having a plurality of transverse ports 24 extending between the side walls 25 of the abutment passages 22—23.

110

The rotor 19 is fixed upon a shaft, and is formed with diametrically opposite slots 27 extending through both sides of the rotor and its periphery, but stopping short of the shaft a distance. These receive snugly and slidably vanes 28, which are radially reciprocable in the slots, and held outwardly by springs 29 which are disposed slidably in suitable bores 30 formed between the opposed slots extending through the interposed body portion of the rotor and the shaft, as may be seen in Fig. 3. The vanes are formed with a suitable number of passages 31 extending from the inner ends and opening on the outer ends, for relief of pressure in the slots 27 when the vanes are pressed inwardly. Formed medially across the outer ends of the vanes there are transverse channels 32, which stop short of the sides of the vanes a distance corresponding to the thickness of the walls 25 of the abutment.

The abutment 18 is held in operative relation with the rotor by means of a spring 33 set in a suitable recess 34 in the element 25 17 of the abutment, this spring being borne upon by an adjustable screw 34' inserted through the top of the casing 10 from without, by which pressure upon the abutment may be regulated. The curve of the face 30 21 of the abutment is such that the abutment will operate as a cam in retracting the vanes and also maintain a close bearing upon the rotor between the vanes to prevent leakage of fluid from the discharge side to the 35 intake side of the pump. The two end face portions of each vane laterally without the channel 32 at the extreme sides of the rotor and extending between the front and back faces of the vane are designated by the 40 numeral 35 (see Fig. 3), while the remaining and intervening two end face portions beside the channel next the front and rear sides of the vane are designated by numerals 36. The part of the face of the circumscribing 45 wall and abutment of the chamber 11 traversed by the surfaces 36 and which will be exposed within the end of the channel 32 as the rotor completes each rotation, will be termed the medial zone. This leaves at each 50 side two lateral zones on the circumscribing wall and abutment which are travelled by respective surfaces 35 of the vane.

The ports 24 are of a width circumferentially of the chamber less than the thickness of the vanes, and the channels 32 are

likewise narrower than the bars 25. Further—and what is most important for the ends in view—the aggregate measurement of the faces 36 circumferentially of the chamber or rotor forms a slightly smaller proportion 60 of the aggregate of the corresponding surface measurements of the medial zone than the similar measurement of each end surface 35 comprises in the corresponding measurement of each lateral zone.

This proportion in the surfaces opposed will permit even wearing without ridges, and avoid vibration or chattering by passing of edges of ports 24 and channels 32.

While the vanes are passing over the ports 24, they will be supported by riding upon the edge portions of the walls 25 and thus striking of the advancing edges of the vanes against the bars of the grill work will be obviated, while even wearing of the parts is 75 assured. As a vane approaches the discharge side of the pump and advances over the grill work, it will be thrust inwardly into the rotor and the water or other liquid previously admitted to the space in the slot 80 27 will be expressed through the passages 31 and discharged through the grill work. When the vanes pass over the grill at the intake side, the vanes are pressed outwardly by the springs and water or other fluid being pumped will be admitted through the passages 31 permitting their free movement outward, as will be readily understood.

What is claimed:—

In a device of the character described, a 90 casing having a cylindrical chamber therein, a cylindrical rotor concentrically revoluble therein, having spring-pressed reciprocable vanes therein, said vanes having channels across their outer ends stopping short of the sides of said vanes, having also passages from the channels through the inner ends of the vanes, an abutment in the chamber, inlet and outlet ports opening on the chamber and of the same width as the 95 channels named, the ratio between the circumferential measurement of the chamber and the width of the vane being less than the ratio between the linear interior surface measurement of the cylinder within the ends 100 of said ports and the corresponding measurement of the vane.

In testimony whereof I have affixed my signature.

FRANK MARION.
